US0D1087000S

(12) **United States Design Patent** (10) **Patent No.:** **US D1,087,000 S**
(45) **Date of Patent:** **** Aug. 5, 2025**

(54) **CHARGER**

(71) Applicant: **Zhejiang Prulde Electric Appliance Co., Ltd., Zhejiang (CN)**

(72) Inventor: **Chenghao Yang, Zhejiang (CN)**

(73) Assignee: **Zhejiang Prulde Electric Appliance Co., Ltd., Zhejiang (CN)**

(**) Term: **15 Years**

(21) Appl. No.: **29/926,209**

(22) Filed: **Jan. 29, 2024**

(30) **Foreign Application Priority Data**

Oct. 23, 2023 (CN) 202330685342.1

(51) **LOC (15) Cl.** **13-02**
(52) **U.S. Cl.**

USPC **D13/108**

(57) **CLAIM**

The ornamental design for a charger as shown and described.

DESCRIPTION

FIG. 1 is a first perspective view of a charger showing my new design;

FIG. 2 is a second perspective view of thereof;

FIG. 3 is a front view of thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line in FIGS. 1-8 illustrate portions of the charger that form no part of the claimed design.
